TOOL HOLDER

Bernard John Bevan, Highland Park, Ill., assignor to Kleinschmidt Laboratories, Inc., Deerfield, Ill., a corporation of Delaware

Application September 11, 1953, Serial No. 379,601

12 Claims. (Cl. 279—14)

The present invention relates to improvements in detachable handles adapted to hold any one of a set of tools of various sizes having similarly formed shanks and more particularly relates to improvements in detachable handles for tools having shanks of L-shape longitudinal configuration.

One of the most commonly used of such tools is the type of wrench used with the well known "Allen" or similar recessed head cap and set screws. These wrenches are conventionally of polygonal cross section and L-shape in longitudinal configuration and are manufactured in sets of varying sizes. These wrenches were originally intended to be used without a handle, but the recessed head cap screw and set screw are now widely used in many applications where they must be tightened to an extent not practical without a handle. Also in many instances such screws are located in areas that are inaccessible with an Allen wrench of normal length.

In addition to wrenches of this general type, other tools such as screw drivers, socket wrenches, augers, hand reamers and the like, are at times provided with shanks of L-shape longitudinal configuration. Examples of such tools and prior art holders therefore are illustrated in United States Letters Patents No. 2,346,364, issued April 11, 1944, to L. H. Dowe for Tool Handle, No. 427,460, issued May 6, 1890, to F. Chantrell for Tool Holder, No. 1,172,656, issued February 22, 1916, to Yorgensen for Wrench Holder, and No. 2,569,069, issued September 25, 1951, to J. Motel for Tool Holder.

One form of prior art handle for use with detachable tool members utilizes a shank milled to conform with the shank of the tool together with a pivotally mounted member and overlying tubular locking means. Such a tool holder is prohibitively expensive and may be used only with tools having a shank of given size.

A further form of prior art tool holder employs a relatively expensive multi-milled slotted tubular sleeve member cooperatively slidably on a milled and bored shank. This form additionally, requires several press fitted guide and lock pins and spring means for biasing the sleeve to a locking position, which results in a relatively complex expensive structure and materially increases the susceptibility of the tool holder to breakage. This form also may be used only with tools of one size.

The present invention is directed to an improved tool holder or handle for detachably holding tools having L-shaped shanks in a wide range of sizes embodying a minimum number of simple, inexpensively manufactured, structurally strong parts which permit quick and easy removal or replacement of tools, and which positively holds the tools in the handle.

The tool holder of the present invention comprises a length of tubing having a hand grip or handle at one end and means at the opposite end for receiving the relatively short laterally extending leg portion of an L-shaped tool shank mounted within the tube. A sleeve is fitted into the

2

tubing in cooperative relation with the tool and positively maintains the tool in a locked operative position with means on the sleeve cooperating with the tube to maintain the sleeve in its assembled position. The material for both the tube and sleeve of the improved tool holder is inexpensive tube stock which is readily available from standard supplies, and easily manufactured by a minimum number of simple drilling and sawing operations which materially lowers the cost of manufacture of the holder. The foregoing will be more fully understood from the detailed structure of the improved tool holder hereinafter to be fully described.

The principal object of the present invention is the provision of novel holders for detachably holding tools which permit rapid and easy attachment to and removal of tools having L-shaped shanks from the tool holder for tool replacement or storage.

It is a further object of the invention to provide improved tool holders for detachably holding tools consisting of a minimum number of simple inexpensively manufactured parts.

Still another object of the invention is to provide improved tool holders adapted to securely hold a wide range of such tools of different shank sizes.

Yet another object of the invention is to provide improved tool holders comprising a simple mounting member for the shank of a tool and a novel locking sleeve coaxially mountable with respect to the mounting member and tool to lock the tool on the member and provided with improved means for retaining the sleeve in its assembled position.

An additional object of this invention is to provide tool holders comprising a pair of hollow tubular members coaxially mountable with respect to each other and the shank of such a tool, and with improved locking means on each member for fixedly securing such a tool in the members.

These and other objects will become more fully apparent from the following description and appended claims when read in connection with the attached drawing, wherein:

Figure 1 is an exploded perspective view showing the components of a preferred embodiment of the present invention;

Figure 2 is a partial perspective view of the tool and holder of Figure 1 in assembled condition;

Figure 3 is a longitudinal sectional view of the assembled tool holder shown in Figure 2;

Figure 4 is an exploded perspective view of a further embodiment of the novel tool holder of this invention;

Figure 5 is a vertical sectional view of the tool holder in Figure 4 shown in assembled position with a tool;

Figure 6 is a vertical sectional view showing the tool holder of this invention holding a wrench; and

Figure 7 is a vertical sectional view similar to Figure 6 showing the tool holder of this invention in assembled position with another form of tool.

Referring now to the drawing and particularly to Figure 1, reference numeral 10 generally indicates a preferred embodiment of the improved tool holder of the present invention comprising metallic tubular member 12, of inexpensive readily available standard tube stock, having an axial bore 13 therein. A conventional screw driver type handle 14 is attached to one end of tube 12 by rivet 15 which extends through the handle and tube 12 and is headed over at diametrically opposite sides of the handle. An aperture 16 is punched or drilled through the wall of tube 12 adjacent its free end.

The preferred embodiment of the present invention will be described in conjunction with an L-shaped polygonal cross section tool, known generally as an "Allen" wrench for use with "Allen" recessed head cap screws and set screws, having an elongate shank portion 18 terminating

at one end in short transversely or right angularly disposed leg portion 20.

Tubular locking sleeve 22, having axial bore 23 therein, is also manufactured from standard tubular stock of an outer diameter just slightly less than bore 13 to permit a sliding fit of sleeve 22 in bore 13, and is cut to predetermined length by a simple sawing or turning operation. One end of sleeve 22 is provided with slot 24 extending diametrically across the end of the sleeve which may be formed by a simple rotary saw operation. Spring arms 25 formed at opposite sides of slot 24, are bent slightly outwardly or away from each other to give the slotted end of sleeve 22 a slightly greater diameter than bore 13. The free end of spring arms 25 are beveled or chamfered as at 27 to permit easy insertion of the sleeve into bore 13 of tubular member 12, as will be hereinafter described. When sleeve 22 is inserted into bore 13, arms 25 due to their resiliency will be compressed inwardly sufficiently to permit insertion of the sleeve 22. In the assembled position, as shown in Figure 3, these arms 25 are biased outwardly against the inner wall of tube 12 to frictionally retain sleeve 22 within the bore.

To assemble the foregoing described improved tool holder and tool as shown in Figures 2 and 3, the tool is inserted into bore 13 of tube 12 with leg 20 of the tool extending transversely to bore 13 and into aperture 16. In some cases it may be necessary to cut off a section of the leg 20 of the tool to permit its insertion into bore 13. Sleeve 22 is then mounted on shank 18 of the tool and slidably moved to the right, as viewed in Figure 3, into bore 13 of tube 12 until back edge 31 of slot 24 abuts the leg 20 of the tool. Sleeve 22 is frictionally retained in this position by the engagement of the arms 25 with the bore 13.

In the assembled position, sleeve 22, which is coaxially mounted in bore 13 of tube 12 in surrounding relation to shank 18 of the tool and in frictional engagement with the walls of the tube, serves to positively lock leg portion 20 of the tool in aperture 16. Thus, the tool cannot be tipped or transversely moved in bore 13 and is positively retained in a predetermined position in the handle.

The preferred embodiment of the improved tool holder of the present invention is unique in its simplicity, since it utilizes a pair of coaxially mountable smooth members that require only a minimum of the simplest machining operations. As a result the improved tool holder of the invention is simple and inexpensive to manufacture and may be easily and quickly assembled and disassembled. Since the bore 23 is cylindrical the assembly may also be used with tools having cylindrical or irregular shanks.

A plurality of sleeves similar to sleeve 22 having axial bores of different diameters may be provided with tool holder 10 to accommodate a series of tools of different shank sizes.

Referring now to Figure 4 there is shown a further embodiment of the invention wherein tubular member 28, having an axially extending bore 30, is provided along its periphery with a plurality of axially spaced openings 32, 34 and 36 of different sizes. A plurality of tubular sleeves 38, 40 and 41 of the same length but of different diameters are similarly provided with transverse diametral end slots 42 of the same depth. As is best illustrated in Figure 5, sleeves 38, 40 and 41 are preferably of the same length and are adapted to be telescopically received one within the other. In this manner, should a tool of a relatively small shank size, such as tool 44, be employed with the novel tool holder of this invention, the three sleeves 38, 40 and 41 can be telescoped one within the other so that the free bore of the smallest, sleeve 41, is operable to receive the shank of the tool with laterally extending leg portion 46 of the tool extending through the

aligned slots 42 of the respective sleeves and into smallest opening 32 in tubular member 28.

Should it be necessary to change from a small shank size tool to a tool of the next larger shank size sleeve 41 can be removed from sleeve 40 thereby increasing the opening in the telescoped sleeves to the next larger bore which is the bore of sleeve 40, to receive a larger size tool. The telescoped sleeves are slidable in bore 30, as heretofore described, and can be moved to a greater depth in bore 30 to engage the laterally extending portion of a tool mounted in opening 34 as indicated at 46' by phantom lines in Figure 5.

Similarly if a tool of even larger size similar to that illustrated in Figure 3 is used, sleeve 40 can be removed from sleeve 38, and the large size shank of the larger tool will be accommodated in sleeve 38 and opening 36, as clearly indicated at 46" by the phantom lines in Figure 5.

With this novel arrangement of telescoping sleeves, with similar depth slots 42, any number of sleeves can be telescoped one within the other to be mounted in tubular member 28 to accommodate tools from the very smallest to a relatively large size. And, any number of openings such as openings 32, 34 and 36 can be provided in the periphery of tubular member 28 to accommodate the laterally extending leg portion of the tool. Thus by merely employing a plurality of inexpensively manufactured tubular sleeves and adapting tubular member 28 for different tool sizes by providing it with a plurality of transverse openings or holes similar to openings 32, 34 and 36, as illustrated in Figure 4, the novel tool holder of this invention is capable of accommodating a wide range of tool sizes.

As clearly shown in Figure 6 the novel tool holder of this invention is applicable to tools other than the "Allen" wrench illustrated in Figure 1 as, for example, socket wrenches 48. In the embodiment illustrated in Figure 6, a wrench mounting member having a shank 50 and transverse end portion or leg 52 is mounted in tubular member 12 in the same manner as shank 18, and is locked therein by sleeve 22. Conventional detachable socket wrench heads 48, can then be mounted on the free end, or left hand end of shank 50 as viewed in Figure 6.

A screw driver 54, or any other form of tool, provided with shank 56 and transverse portion or leg 58 as illustrated in Figure 7 can be similarly mounted in the novel tool holder of this invention in the manner heretofore described. It is to be understood that the embodiments of Figures 6 and 7 can be made or modified to be like that shown in Figure 5 to accommodate a wide range of shank sizes.

From the foregoing it will be readily appreciated that there is herein provided a novel relatively simple tool holder for detachable tools that is quickly and easily assembled and disassembled, embodies a minimum number of inexpensively manufactured structurally strong elements, assures the application of sufficient force to the tool for a particular task, and effectively and simply lengthens the tool to reach inaccessible locations.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A tool holder for tools having shanks provided with a transverse leg comprising, a hollow member for receiving the shanks of such a tool therein, means in said hollow member for drivingly engaging the transverse leg of the tool, and means mountable in said member in coaxial relation with said member and surrounding a por-

tion of the shank of the tool therein to positively lock and maintain such a tool in, and coaxial relative to, said member.

2. The device as set forth in claim 1 together with means to retain said last named means in its assembled position.

3. In combination, a tool holder comprising an elongate hollow shank, an aperture in the hollow shank wall adjacent one end of the shank, a tool having an extended straight shank and an offset projection at one end, said one end being adapted to pass into said hollow shank and have the projection extending into said aperture with a close fit, and a hollow sleeve slidable over said tool shank and of sufficient length and fit to maintain the axis of said tool shank coaxial with the axis of said sleeve and passing into said hollow shank with a sliding fit a sufficient distance to maintain the tool shank and sleeve axes coaxial with the hollow shank axis whereby the tool shank projection will be maintained in interlocked engagement with the wall of said hollow shank and the tool will be a substantially coaxial projection of the hollow shank.

4. A tool holder as defined in claim 3 and means for holding said sleeve within said shank.

5. In combination, a tool holder comprising a hollow shank provided with a series of apertures of different size, a tool selected from a series of tools each having a transversely extending leg, said tool being individually inserted in said shank with the leg engaging one of said apertures, at least one of a plurality of hollow sleeves each adapted to selectively receive a particular size tool of said series mounted within said hollow shank in surrounding relation to a portion of such tool, and means for holding the sleeves within said shank to thereby lock said tool in said tool holder.

6. A tool holder for detachably holding tools comprising, a pair of smooth hollow tubular members adapted to be mounted in coaxial relation with respect to each other, a tool having an elongate portion and an offset portion, means on one of said members adapted to drivingly engage said offset portion of said tool mounted in said one member, the other member being adapted to surround said elongate portion of the tool to maintain said offset portion in driving engagement with said means and thereby lock the tool in said one member, and means on said other member to frictionally engage said one member to retain said other member in said one member.

7. A tool holder for tools having L-shaped shanks comprising an elongate tubular member having a handle secured at one end and an aperture extending through the wall adjacent the other end for engaging one leg of the shank of such a tool when mounted in said tubular member, a hollow sleeve adapted to be mounted in said tubular member in coaxial relation between said member and the shank of such a tool when mounted therein, and spring arms at one end of said sleeve to frictionally engage said member and lock said sleeve in said member.

8. A tool holder for a tool having a shank of L-shape in longitudinal configuration and comprising an elongate tubular member having a handle at one end, at least one aperture adjacent the other end of said member for drivingly engaging a transversely extending leg of the shank

of such a tool when mounted in said member, a sleeve having a coaxial bore and insertable into such member in surrounding relation to a portion of the shank of such a tool within said member, said sleeve being adapted to thereby maintain said tool shank substantially coaxial with said tubular member and lock the leg of such a tool in said aperture in said member.

9. A tool holder for tools having elongate shanks with a substantially transverse leg at one end of the shank 10 comprising an elongate tubular member having a handle secured at one end and an aperture through the wall adjacent the other end for engaging said leg of such a tool when mounted in said tubular member, a hollow sleeve adapted to be mounted in said tubular member 15 in coaxial relation between said member and the shank of such a tool when mounted therein, and resilient means at one end of said sleeve to engage said member and retain said sleeve in said member.

10. A tool holder comprising a smooth elongate member 20 having an axial passage for receiving a shank of a tool to be held in said tool holder, at least one opening in said member transverse to said passage for receiving a transverse leg portion of the shank of a tool mounted therein, a handle secured at one end of said member, 25 hollow means having an outside dimension to permit a coaxial sliding close fit of said hollow means in said member and an inside dimension to slidably receive, with a close fit, the shank of the tool mounted in said member to retain said leg in said opening and thereby 30 lock the tool in said member.

11. A tool holder comprising an elongate member having an axial passage for receiving a shank of a tool to be held in said tool holder, at least one opening in said member transverse to said passage for receiving a transverse leg portion of the shank of a tool mounted therein, a handle secured at one end of said member, hollow 35 means comprising a plurality of sleeves each having an axial bore and being telescoped one within the other and the outermost sleeve having an outside dimension to permit a coaxial sliding fit in said axial passage and the axial bore of the innermost sleeve receiving the shank of the tool mounted in said member to retain said leg in said opening and thereby lock the tool in said member whereby a predetermined plurality of said sleeves can be 40 telescoped together to accommodate a particular size tool shank.

12. The device as set forth in claim 11 wherein said sleeves are provided with aligned slots at one end, the sides of said slots being bent outwardly slightly so that each sleeve frictionally engages the sleeve in which it is mounted and the outermost sleeve engages the sides of the axial passage to thereby retain said sleeves within one another and in said member.
